UNITED STATES PATENT OFFICE.

JOSEPH E. EVANS, OF BEDFORD, INDIANA, ASSIGNOR OF ONE-FOURTH TO CHARLES S. KNIGHT, OF CHICAGO, ILLINOIS.

SUSPENSION DEVICE FOR EQUALIZING THE STRAIN ON ELEVATOR CABLES.

Application filed August 13, 1923. Serial No. 657,038.

To all whom it may concern:

Be it known that I, JOSEPH E. EVANS, a citizen of the United States, residing in Bedford, county of Lawrence, and State of Indiana, have invented certain new and useful Improvements in Suspension Devices for Equalizing the Strain on Elevator Cables, of which the following is a specification.

10 My invention relates to improvements in devices for equalizing the strain on cables used for hoisting and lowering elevator cars in common use for transferring passengers and freight from one floor of a building 15 to another, especially high buildings where the lift is of considerable height. My present invention relates to devices of the general type described in Patent No. 1,442,030 granted to me on January 16, 1923, and the 20 general purpose of my invention is to perfect and improve the equalizing device therein shown. One object of my invention is to simplify and strengthen the construction by the use of a unitary guide and safeguard 25 plate instead of a plurality of members employed for that purpose. Another object is to provide an arrangement and construction of parts through which the device is adapted 30 to be employed with an odd number of cables. Another object is the provision of deflector means by means of which the two cables at opposite ends of an equalizer bar are prevented from spreading, thus enabling 35 the device to be used in situations where the suspension cables pass through small openings in the motor frame or a floor which would otherwise interfere with the operation of the device. Other objects relate 40 to improvements in the manner in which the trunnion blocks are mounted in the equalizer bars, and the manner of connecting the ends of the suspension cables to the trunnion blocks in the equalizer bars. 45 With these and incidental objects and advantages in the construction and arrangement of parts in view, I have devised and invented the improved suspension device hereafter described in detail, my invention residing 50 in the novel construction and arrangement of parts and combination of cooperating members which I have devised for the ends in view, the essential elements of my invention being more particularly pointed out in the appended claims.

55 In the accompanying drawings forming

a part of this specification, Figure 1 is a side elevation, on a small scale, showing portions of an elevator apparatus of a common type to which my invention is shown applied; Fig. 2 is a side view of the equalizing device alone, on a larger scale; Fig. 3 is a detail section showing the manner of attaching the suspension cables to the equalizer bars, on a plane indicated by the dotted lines 3-3 of Fig. 2; Figs. 4 and 5 are respectively a top plan view and a perspective of the device; Fig. 6 is a plan view of the lower frame plate, detached; Fig. 7 is a diagrammatic view illustrating the relationship of the equalizing cable and suspension cables and the connection upper and lower sheaves, developed in a single plane; Fig. 8 is a top plan view of a modified form of my invention applied to an elevator car suspended by an even number of cables; Fig. 9 is a detail showing a modified manner of connecting the suspension cables to the equalizer bars; and Fig. 10 is a view illustrating a modified form of deflector for preventing spread of the suspension cables.

The same reference characters indicate the same parts in all the figures of the drawing.

It will be understood that as in the case of the equalizing device described in my issued patent above referred to, my present invention is intended to be applied to equalize the strain between the separate cables of a group of cables employed to suspend an elevator car and arranged to all run over a suspension drum or pulley at the top of the elevator shaft, see Fig. 1. An even number of cables, frequently six in number, is commonly employed for the purpose, and the equalizing device of my patent before mentioned is intended to be applied to such an installation, but it frequently occurs that an odd number of cables, for instance three, five, or seven, is used. In Figs. 1 to 5, inclusive, I have shown my invention applied to the suspension of a car by an uneven number of cables, five in the particular instance, and in Fig. 7 I have illustrated diagrammatically the relationship of the equalizing members.

My equalizing device is designed to be secured to the elevator car through two properly spaced bars 1-1 which structurally form a part of the car and may be either an integral portion of the car frame,

or be safely secured thereto. Underlying the bars 1 is arranged a lower plate 2, and above the bars an upper plate 3, forming a guide and safety member, the two plates 5 being clamped to the bars by means of bolts 4, both plates preferably consisting of suitably formed steel castings, and forming, together with the bolts the frame of the suspension device.

10 The lower plate is formed with integral bearing brackets or lugs 5 bored to receive journals of the lower sheaves 6 and 6^a and orificed to receive the connecting bolts 4. It is also formed with at least one slot to 15 receive the end of the equalizing cable 7, as indicated at 8 in Fig. 6, and may be provided on the opposite side also with a similar slot 8^a, as illustrated, whereby the same form of plate may be used for installing an equalizer for either five or six cables, as hereinafter explained.

18 The upper plate is of the hollow and curved form shown in the drawings, having base flanges 9 adapted to bear on the top faces 25 of the bars 1, and an arched upper portion provided with external strengthening ribs 10 and 10^a and bearing shoulders 11, and is formed with opposite side openings 12 arranged to receive the equalizer bars herein- 30 after mentioned. As shown the top may be provided with openings 13 for observation purposes, and extending from near the center line of the plate the outer rib marked 10^a is branched around an opening 14 provided 35 to receive one end of the equalizing cable 7. The branches of the rib are orificed to receive the journal of a guide pulley 15 engaged by the equalizing cable. The shoulders 11 and base flanges 9 are provided with 40 aligned openings to receive the connecting bolts 4.

45 The upper sheaves 16 and 16^a are each journaled centrally between a pair of equalizer bars 17 which at their opposite ends are connected to a pair of adjacent oppositely spread suspension cables (marked A and A') and function in unison as a single bar. These bars and sheaves are set in parallel 50 planes slightly oblique to a vertical plane passing through the periphery of the suspension pulley so that the oppositely spread suspension cables will all track from the ends of the equalizer bars correctly into the grooves of the suspension pulley. The lower 55 sheaves are oppositely inclined so that the equalizing cable, which is anchored at one end of the car may track in succession in a staggered or zig-zag path over the upper sheave 16, under the lower sheave 6, over 60 the upper sheave 16^a, under the lower sheave 6^a, and thence to the guide pulley 15, above which it is secured to the outermost suspension cable (marked A) at that side of the 65 group of suspension cables. The anchored end of the equalizing cable is secured to a

socket block 7^a below the lower plate and having a flared end within which the strands of the cable are spread and the space filled with Babbitt metal.

70 For the purpose of conveniently and securely connecting the suspension cables to the ends of the equalizer bars I have provided novel connecting means, best shown in Figs. 2 and 3, by reference to which it will be seen that the ends of each cable are 75 secured (by Babbitt metal) to a socket piece 17^a, above which, loosely surrounding the cable, is arranged a loose externally threaded sleeve 18. The sleeve passes loosely through a block 19 provided with trunnions 20 arranged to be received in aligned downwardly opening bearing slots 21 at each end of the pair of equalizer bars. Washers 22 and cotter pins 23 and a small set screw 22^a passing through the washer 22 and engaging a threaded seat in the equalizer bar are provided to maintain the parts 80 of this pivot bearing in assembled relation. Bearing against the lower face of the trunnion block is a pair of nuts 24 engaging the sleeve 18, which nuts carry the load on the connected cables and provide for adjustment so that the equalizer bars may all be brought to horizontal position at a selected 85 point for adjusting the device, preferably 90 midway of the path of the car.

95 In Figure 9 I have illustrated another form of connection consisting of a small pulley 25 rotating on a shouldered pivot 100 bolt 26 seated in the slots 21 of the equalizer bars, the suspension cable being lopped around the pulley and its free end clamped to the portion leading to the suspension pulley.

105 For the purpose of reducing the spread of the opposite suspension cables attached to a pair of equalizer bars I have provided a deflector consisting of a pair of plates 27-27^a separated by spacing blocks 27^b and rigidly secured to the upper end of a flat 110 tie-bar 28 which at its lower end is secured by a pivot bolt to the center of the corresponding strengthening rib of the plate 3, and a pair of rollers 29-29 which respectively engage the two cables of the pair. 115

120 In Fig. 10 I have illustrated a modified form of deflecting means for restraining spread of the suspension cables, consisting of a pair of matched clamping plates 30-30^a arranged to be clamped together upon a cable at one end and orificed to receive clamping bolts by which it is secured to such cable a short distance above the top of the suspension device. The clamping plates extend laterally to provide a bearing for a shouldered pivot bolt 31 at the other end of the deflector, and on this pivot bolt is rotatably mounted a small idler 125 sheave 32 which engages the suspension cable at that end, or side, of the device. 130

In Figure 8 (and also Fig. 6) I have illustrated my invention as applied to an even number of cables,—six in the particular instance. In this case the outer ribs 5 are all alike, the opening 14 and branches of the rib marked 10^a in describing the form first above mentioned being omitted. In this case, also, the equalizing cable, marked 7^b, is anchored at both ends to the 10 lower plate, the two ends of the cable passing respectively through the slots 8 and 8^a of the plate and both being provided with socket blocks 7^a engaging the lower face of the plate adjacent the slots. 15 As will be seen by examination of the diagrammatic view marked Fig. 7, the strain upon each reach of the equalizing cables must be equal, as well as the strain communicated to the several suspension 20 cables, in the form of my invention applied to a group of an odd number of cables; while in the form of my present invention as applied to an even number of cables, the strain reactions are the same as in the 25 equalizer described in my prior patent.

I claim:

1. A suspension device for connecting an elevator car to an uneven number of suspension cables comprising a plurality of 30 sheaves pivotally connected with all of said cables excepting one in pairs and a like plurality of sheaves pivotally secured to the car, and an equalizing cable anchored at one 35 end to the car and connected at the other end to said excepted one of the suspension cables and engaging said first-mentioned sheaves and said second-mentioned sheaves in alternation.

2. A suspension device for connecting an elevator car to an uneven number of suspension cables comprising a plurality of 40 sheaves pivotally connected with all of said cables excepting one in pairs and arranged side by side in parallel planes, and a like 45 plurality of sheaves pivotally secured to the car and arranged side by side also in parallel planes, and an equalizing cable anchored at one end to the car and connected at the other end to said excepted one of the 50 suspension cables and engaging said first-mentioned sheaves and said second-mentioned sheaves in alternation.

3. A suspension device for connecting an elevator car to an uneven number of suspension cables comprising a plurality of 55 sheaves pivotally connected with all of said cables excepting one in pairs and arranged side by side in parallel planes, and a like 60 plurality of sheaves pivotally secured to the car and arranged side by side also in parallel planes, and an equalizing cable anchored at one end to the car and connected at the other end to said excepted one of the suspension cables and engaging said 65 first-mentioned sheaves and said second-

mentioned sheaves in alternation; said first-mentioned and said second-mentioned sheaves being oppositely inclined in staggered relation.

4. A suspension device for connecting an elevator car to an uneven number of suspension cables comprising a set of equalizer bars respectively connected at their opposite ends with all of said suspension cables excepting one in pairs, a corresponding set 70 of sheaves respectively journaled centrally in said bars, a second set of sheaves pivotally secured to the car, and an equalizing cable anchored at one end to the car and at the other end connected to said excepted 75 one of the suspension cables and engaging said first-mentioned and said second-mentioned sheaves in alternation.

5. A suspension device for connecting an elevator car to an uneven number of suspension cables comprising a set of oscillatory equalizing members respectively oppositely connected with all of said suspension cables excepting one in pairs, a corresponding 80 set of sheaves pivotally connected with 85 said oscillatory members, a second set of sheaves pivotally secured to the car, and an equalizing cable anchored at one end to the car and at the other end connected to said excepted 90 one of the suspension cables and engaging said first-mentioned and said second-mentioned sheaves in alternation.

6. In a suspension device for connecting an elevator car to a plurality of suspension 100 cables and having a set of equalizer bars oppositely connected to pairs of said cables, means for restraining the spread of the cables of a pair comprising a deflector device connected with said suspension device a short distance thereabove and engaging 105 both cables of the pair.

7. In a suspension device for connecting an elevator car to a plurality of suspension cables and having a set of equalizer bars 110 oppositely connected to pairs of said cables, means for restraining the spread of the cables of a pair comprising a deflector device connected with said suspension device a short distance thereabove and engaging 115 both cables of the pair, said deflector device including at least one idler sheave engaging one of said cables.

8. In a suspension device for connecting an elevator car to a plurality of suspension 120 cables and having a set of equalizer bars oppositely connected to pairs of said cables, means for restraining the spread of the cables of a pair comprising a tie bar anchored to the suspension device, a frame secured to the upper end of said tie bar, and 125 a pair of rollers rotatably mounted in said frame and respectively engaging the cables of the pair.

9. In a suspension device for connecting an elevator car to a plurality of suspension 130

cables and having a set of equalizer bars connected each at its opposite ends to a pair of equalizer cables, a guide and safety plate consisting of an integral metal casting arranged to be secured to the car and having side openings arranged to receive and guide said bars.

10. In a suspension device according to claim 9, a guide and safety plate according to said claim having an arched top and parallel sides and opposite base portions arranged to seat upon structural members of the elevator car.

11. A suspension device of the character described having a frame consisting of an integral laterally-orificed upper plate and a lower plate arranged to bear respectively against the upper and lower faces of spaced structural members of the elevator car, and connecting bolts passing between such members and arranged to clamp said plates thereto.

12. In a suspension device of the character described and including pairs of equalizer bars and suspension cables, means for pivotally connecting a cable to the end of a pair of bars comprising a socket piece secured to said cable, an exteriorly threaded tube loosely engaging said cable and abutting against said socket piece, a block piv-

otally mounted between said pair of bars and having an orifice loosely engaging said threaded tube, and an adjusting nut engaging said tube below said block and arranged to bear against the lower face thereof.

13. In a suspension device of the character described and including pairs of equalizer bars and suspension cables, the ends of the bars being formed with downwardly-opening slots adjacent their ends, means for securing a suspension cable to a pair of bars comprising a cross pivot member arranged to engage said slots and connected to said cable between said bars, a washer on said pivot member outside its adjacent bar, and a set screw passing through said washer and seated in such bar.

14. In a suspension device of the character described and including pairs of equalizer bars and suspensions cables, the ends of the bars being formed with downwardly-opening slots adjacent their ends, means for securing a suspension cable to a pair of bars comprising a cross pivot member arranged to engage said slots and connected to said cables between said bars, and means for restraining said pivot member against displacement from said slots.

JOSEPH E. EVANS.
